Primary Examiner — Clare Ann Gannon

(74) *Attorney, Agent, or Firm* — Cabilly & Co.

(57) **CLAIM**

The ornamental design for a corner device for a floor covering, as shown and described.

DESCRIPTION

FIG. 1 is a perspective view showing a face of the corner device for a floor covering;

FIG. 2 is a plan view of the face thereof;

FIG. 3 is a plan view of an opposite face thereof;

FIG. 4 is a plan view of an edge thereof;

FIG. 5 is a plan view of an opposite edge thereof;

FIG. 6 is a plan view of an end thereof; and,

FIG. 7 is a plan view of an opposite end thereof.

1 Claim, 3 Drawing Sheets
